CUP

Willis Allison Stageberg, Minneapolis, Minn., assignor to
Plastics, Inc., St. Paul, Minn., a corporation of Minnesota

Application June 20, 1958, Serial No. 51,442

Term of patent 14 years

(Cl. D44—9)

FIG. 1

FIG. 2

FIG. 3

FIG. 4

Figure 1 is a top plan view of a cup showing my new design;

Figure 2 is a side elevational view of the same;
Figure 3 is an end elevational view of the same; and
Figure 4 is a bottom plan view of the same.

I claim:

The ornamental design for a cup, as shown.
